HANGER

Joseph M. Margolis, % Jiffy Enterprises, Inc.,
146-150 13th St., Philadelphia, Pa. 19107

Filed Apr. 22, 1966, Ser. No. 1,980

Term of patent 14 years

(Cl. D54—1)

FIG. 1

FIG. 2

FIG. 5

FIG. 3

FIG. 4

FIG. 6

I claim:

The ornamental design for a hanger, substantially as shown.
